SHOWER CURTAIN

Nathaniel Gaines, South Orange, N. J.

Application November 26, 1940, Serial No. 367,197

9 Claims. (Cl. 156—10)

This invention relates to curtains, and more particularly to water repellent shower curtains for use in bath rooms, both as a decorative feature and for preventing excessive splashing of the shower water.

Owing to the universal construction of curtain supports about bath tubs equipped with showers, and open showers in bath rooms, it has heretofore been extremely difficult, if not impossible, to provide a structure of water repellent curtain which embodied the advantages of quick and easy attachment to or detachment from the curtain rod, and sliding movement along the curtain rod, which curtain was at the same time neat, attractive and artistic.

It has heretofore been the universal practice in constructing such shower curtains to insert a plurality of grommets in the upper edge or hem of the curtain at points spaced along the edge of the curtain such as the maker thought to be proper. Such grommets, being metal, are unsatisfactory in themselves, especially when used in high grade curtains, where they detract from the otherwise artistic appearance of the curtains. Frequently they rust with use, causing rusty, unsightly streaks on the curtain, and also they permit only of limited, fixed points of suspension of the curtain from the pole or rod, which in a number of installations causes improper arrangement of the folds of the curtain, and causes such improper folds and unsightly hanging of the curtain in all installations unless unusual care is taken to properly arrange the curtain when it is pushed back.

Various ways have been devised to hide these unsightly grommets, such as by providing upstanding ruffles along the upper hem of the curtain, but these ruffles fall down and assume irregular shapes and become unsatisfactory in themselves, without in any way overcoming the disadvantages of the limited fixed points of suspension and the probability of rusting grommets with the attendant discoloration of the curtain.

The object of the present invention is to provide a shower curtain which completely dispenses with the use of grommets and their disadvantages and provides an artistic, practical curtain embodying means for attaching supporting hangers thereto, which means also serves as a decorative feature of the curtain and provides for an unlimited variation in the number and placement of the connections of the hangers to the curtain, resulting in the insurance of proper and artistic hanging of the curtain. Said means also serves as a reinforcement of the upper edge or

hem of the curtain, preventing buckling under the weight of the suspended curtain.

With these and other objects in view, as may appear from the accompanying specification, the invention consists of various features of construction and combination of parts, which will be first described in connection with the accompanying drawings, showing a shower curtain of the preferred form embodying the invention, and the features forming the invention will be specifically pointed out in the claims.

In the drawings:

Figure 1 is a fragmentary view of a shower curtain constructed in accordance with the present invention, showing the manner of suspending it.

Figure 2 is a fragmentary view of a curtain having parts broken away to illustrate the manner of connecting the decorative, reinforcing, hanger attaching structure to the curtain.

Fig. 3 is a cross-section taken on the line 3—3 of Figure 2.

Figure 4 is a detail illustration of the decorative, reinforcing, hanger engaging tape used with the curtain.

Figure 5 is an enlarged detail of the tape.

Figure 6 is a fragmentary view of a shower curtain showing a modified form of the invention.

Figure 7 is a fragmentary view of a further modified form of the invention.

Figure 8 is a fragmentary side elevation, with parts broken away, of a further modified form of the invention.

Figure 9 is a fragmentary side elevation of the decorative hanger loop forming edging, as shown in Figure 8.

Figure 10 is a fragmentary view of a shower curtain showing a still further modified form of the invention.

Figure 11 is a view in section through a clip embodied in the modified form shown in Figure 10, taken approximately on the line 11—11 of Fig. 10.

Referring more particularly to the preferred form of the invention shown in Figures 1 to 5 inclusive of the drawings 10 indicates the curtain body, which may be made of any suitable water repellent fabric to provide any desired artistic appearance and design. Various types of fabrics are used for this purpose, all being water repellent, and the curtain bodies being of considerable size causes the curtains to be relatively heavy. It is also necessary that the curtains may be slid along their supporting rods, such as shown in Figure 1, at 11, so as to enclose the tub or shower, or to open it. In consideration of this feature, and

of the weight of the curtain, a number of points of suspension are required for the curtain. As above stated, it has heretofore been the practice to insert a plurality of grommets in the curtain along its upper edge to provide a plurality of reinforced openings for receiving curtain hangers of various types, an approved type of which is shown at 12 in Figure 1. Such grommets are in themselves unsightly, and they provide unsightly and undesirable connections with the curtain hangers 12, resulting in buckling of the upper edge of the curtain as well as causing the curtain to hang in improper and unsightly folds in that they permit only limited points of suspension, while different installations require different points and different numbers of points of suspension to obtain the best appearance.

The present invention provides an unlimited variation in the positioning of the points of suspension of the curtain 11 upon the hangers 12, and at the same time not only eliminates the unsightly grommets, but provides an artistic edging for the upper hem or edge of the curtain.

A reinforcing tape 14, shown in detail in Figures 4 and 5 of the drawings, is provided. This tape consists of a webbing 15, woven of a plurality of spaced threads so as to provide reinforcement of the upper edge or hem of the curtain without stiffening the upper edge of the curtain overmuch and without interfering with the flexibility of the curtain. The webbing 15 of the tape has a cord 16 connected thereto at regularly spaced points along its length, said cord being doubled in and through certain of the interlocking stitches 18 of the upper edge of the web body 15 of the tape (as is clearly shown in Figure 5 of the drawings). In order to provide a firm and secure connection between the cord 16 and the tape 14, and also to provide a plurality of regular loops along the upper edge of the tape, all of uniform size, each has its points of connection to the tape at longitudinally evenly spaced points along the length of the tape, and consequently along the upper edge or hem of the curtain body 10. These loops provide a decorative fringe along the upper edge of the curtain body 10 and also provide loops for the attachment of the hangers 12 to the curtain body 10. By making these loops 16 relatively small, and of the proper size to add to the appearance of the curtain, practically an unlimited number of relative positions of connection between the hangers 12 and the curtain body 10 may be provided and the hangers may be spaced at practically any desired points along the length of the curtain, without being limited to specific points of connection, as when grommets are used.

In constructing the curtain the top edge of the curtain is folded over, as shown at 17, and the reinforcing tape is placed flat against this side of the fabric of the curtain body, with its upper edge flush with the upper edge of the fold of the curtain body. A binding strip 18, preferably of the same material as the curtain body 10, is then placed against the outer side or surface of the reinforcing tape 14. The upper edge of this binder strip is folded under, with the edge of the fold flush with the upper edge of the tape 14 as well as with the upper edge of the fold at the top of the curtain body 10. The lower edge of the binder strip 18 is folded around the lower edge of the web 15 of the tape 14, lying flat against the curtain body 10, concealing the lower edge of the tape 14. The binder strip 18, 75

reinforcing tape 14 and the curtain body 10 are then stitched together along the lower and upper edges of the binding strip 18, as shown at 20, securely and firmly attaching the reinforcing, loop carrying tape 14 to the upper edge of the curtain.

In Figure 6 of the drawings, the top edge of the shower curtain body 10' is folded over and stitched, as shown at 30, to provide a reinforcement for the upper or top edge of the curtain. A plurality of grommets 31 are attached to this top edge of the curtain 10' at spaced points. These grommets 31 are of fabric, and may be attached to the top edge of the shower curtain by stitching. They may be of any desired color, to blend with the color scheme of the shower curtains. A cord 32 is looped through the grommets 31, to provide a plurality of hanger engaging loops 33, which are engaged by the hangers 34. In the drawings the hangers 34 are shown as of an artistic type of hanger, made of plastic, which engage over the curtain rod 35, but it is to be understood that these hangers form no part of the present invention.

The cord 32 is looped about the grommets, as clearly shown at 36, so that when the loops 33 are free from tension, the connection or engagement between the cord 32 and the various grommets will be loose, permitting adjustment of the size of the individual loops 33. But when the curtain 10' is suspended from the rod 35 by means of the hangers 34, the tension on the cord 32, through its engagement with the hangers, will cause a binding of the looped portions 36 with the grommets 31 and prevent the cord from slipping and consequently altering the size of the various loops. The cord 32 may be made of any suitable material, in any suitable color, to blend with the color scheme of the shower curtain.

The cord, together with the grommets 31, forms a decorative top edging for the shower curtain.

The modified form shown in Figure 7 of the drawings is quite similar to that shown in Figure 6, differing therefrom only in the fact that the fabric grommets 31' are inserted in the folded-over, reinforcing top end or hem 37 of the shower curtain 10', rather than being attached or connected to the top edge of the shower curtain. The cord 32' is passed through the grommets 31' and looped therethrough, as shown at 36', so as to permit adjustment of the size of the loops 33' when such loops are free from tension resulting from the supported weight of the shower curtain 10'. These loops 36', when the weight of the shower curtain is carried by them, bind tightly on the grommets 31' and prevent slippage of the cord 32'.

In Figures 8 and 9 of the drawings, the same principle of the looped cord for permitting adjustment of the size of the individual loops is employed, but there is provided a different manner of attaching the cord to the shower curtain.

The cord 40, in this modified form of the invention, as shown at 41 is looped at spaced points around and over a cord or upper section 42 of the reinforcing, connecting member 43. The member 43 may be in the form of a web tape, similar to the tape 15 shown in Figures 1 to 5 inclusive, or it may be a series of parallel, extensive cords 42 and 44, connected at spaced points by vertical connecting elements 45. The connecting member 43 is placed against one side of the top edge or hem of the shower curtain 46, and a covering or binding strip 47 is placed over the outer exposed side of the member 43. The cover strip 47

is stitched to the curtain 46, as indicated at 48, and one row of the stitching, namely that shown at 48', is positioned so that it will extend through the parallel cord 44, or a portion of the web or member 43 below the cord 42, thus leaving the cord 42 loose or free from direct attachment to the curtain body 46, so that the size of the hanger engaging loops may be adjusted, if desired, when such loops 49 are free from tension occasioned by suspension of the weight of the curtain 46. The cord 48 may be of any suitable material and color, according to the shower curtain upon which it is used. As in all of the other forms of the invention, it will be apparent that this method of providing means for suspending the shower curtain from a curtain rod provides a decorative edging for the top edge of the curtain.

Figures 10 and 11 depart slightly from the various other forms of the invention shown, but are generally related to all of the other forms in that a cord is employed for providing the hanger engaging loops for supporting the shower curtain.

In this form, however, a reinforcing cord 50 is inserted through a hem 51 formed along the upper edge of the shower curtain 52. The cord 53 forming the hanger engaging loops 54 is connected to the top edge of shower curtain by means of a plurality of resilient clips 55. The clips 55 are preferably made of plastic, and when used with the plastic hangers 34 may be of the same color, providing an attractive appearance. The clips 55 are shaped so as to firmly grip the cord 53 and the hem 51, but providing sufficient freedom to permit adjustment of the cord 53 to vary the size of the loops 54. The ends of the cord 53 are attached to the shower curtain at its edges in any suitable manner.

In all of the various forms of the invention, a cord is employed, which is connected at spaced points along the upper edge of the shower curtain to provide loops for engagement with any suitable type of curtain hanger, and these cords are embodied in the general organism of the shower curtain in such manner as to provide an artistic, decorative edging for the top hem of the shower curtain.

It will be understood that the invention is not to be limited to the specific construction or arrangement of parts shown, but that they may be widely modified within the invention defined by the claims.

What is claimed is:

1. In a shower curtain, a curtain body, a reinforcing member along the upper edge of said body against one side of the body, a binding strip over the side of the reinforcing member away from the curtain body, said reinforcing member and binding strip being stitched together and to said curtain body, a plurality of open loops along the upper edge of the reinforcing member and extending beyond the edge of the curtain body, each loop having its two points of connection with the reinforcing member spaced longitudinally along the edge of the curtain body to form a decorative edging for the curtain top and also to provide for the connection of supporting hangers to the curtain.

2. In a shower curtain, a curtain body, reinforcing means along the upper edge of said body against one side of the body, a binding strip over the side of the reinforcing means away from the curtain body, said reinforcing means and binding strip being stitched together to said curtain body along both their upper and lower edges, a plurality of open loops along the upper edge of the

reinforcing means and extending beyond the edge of the curtain body, each loop having its two points of connection with the reinforcing means spaced longitudinally along the edge of the curtain body to form a decorative edging for the curtain top and also to provide for the connection of supporting hangers to the curtain, said binding strip having its lower edge turned to engage against the curtain body and enclose the lower edge of the reinforcing means.

3. In a shower curtain, a curtain body, a hanger loop forming member connected to the upper edge of the curtain body at a plurality of spaced points to form a plurality of loops along the top edge of the curtain body, said member being adjustably connected to said curtain body by slideable frictional engagement so that when the loops are relieved of tension the connections may be adjusted to vary the size of the individual loops and when under tension will securely bind to support the curtain and prevent slippage of the member relative to the curtain.

4. In a shower curtain, a curtain body, a decorative edging along the top edge of the curtain body and comprising a cord connected to the curtain at spaced points along its length to provide hanger engaging loops, the two points of connection of each loop with the curtain body being spaced longitudinally along the upper edge of the curtain body and adjustably connected thereto by slideable frictional engagement so that when the loops are relieved of tension the connections may be adjusted to vary the size of the individual loops and when under tension will securely bind to prevent slippage of the cord relative to the curtain.

5. In a shower curtain, a curtain body, a decorative edging along the top edge of the curtain and comprising a cord, means carried by the top edge of the curtain body to facilitate connection of the cord to the curtain body, said cord being adjustably connected to said means by slideable engagement to form a plurality of loops along the top edge of the curtain body and so that when the loops are relieved of tension the connections may be adjusted to vary the size of the individual loops and when under tension will securely bind to prevent slippage of the cord relative to the curtain.

6. In a shower curtain, a curtain body, a decorative edging along the top edge of the curtain and comprising a cord, means carried by the top edge of the curtain body to facilitate connection of the cord to the curtain body, said cord being looped completely around portions of said connection means to provide a plurality of longitudinally spaced hanger engaging loops along the top edge of the curtain body.

7. In a shower curtain, a curtain body, a decorative edging along the top edge of the curtain comprising a plurality of fabric grommets carried by the curtain body at its top edge and at spaced points therealong, and a cord connected to said grommets to provide a plurality of hanger engaging loops along the top edge of the curtain body, said cord being looped through said grommets in slideable frictional engagement with the grommets so as to permit adjustment of the size of the individual loops when the cord is free from tension and to securely bind against the grommets when the cord is under tension occasioned by the weight of the supported curtain.

8. In a shower curtain, a curtain body, a reinforcing member along the upper edge of said body, a cord looped through the upper edge of

said reinforcing member and forming a plurality of loops extending beyond the edge of the curtain body, said loops being spaced from each other a distance substantially equal to the size of the loops to provide a decorative scalloped appearing edge along the top of the curtain body.

9. In a shower curtain, a curtain body, a reinforcing member attached along the upper edge of said body, a cord sinuously bent to form a

5 plurality of loops all of substantially uniform size, said loops alternately extending outwardly from and inwardly to the edge of the curtain body, said inwardly extending loops being rigidly connected at their apices to said reinforcing member to maintain the decorative edging effect of the loops at all times.

NATHANIEL GAINES.
